DESIGN FOR A HEATING-STOVE.

SPECIFICATION forming part of Design No. 13,918, dated May 22, 1883.

Application filed April 23, 1883. Term of patent 7 years.

UNITED STATES PATENT OFFICE.

H. CLAY BASCOM, OF TROY, AND TOBIAS S. HEISTER, OF LANSINGBURG,
ASSIGNORS TO SHERMAN S. JEWETT & CO., OF BUFFALO, NEW YORK.

DESIGN FOR A HEATING-STOVE.

SPECIFICATION forming part of Design No. 13,918, dated May 22, 1883.

Application filed April 23, 1883. Term of patent 7 years.

To all whom it may concern:

Be it known that we, H. CLAY BASCOM, a citizen of the United States, residing in the city of Troy, in the county of Rensselaer and State of New York, and TOBIAS S. HEISTER, a citizen of the United States, residing in the village of Lansingburg, in said county and State, have jointly invented and produced a new and original Design for a Heating-Stove, of which the following is a specification, reference being had to the accompanying photograph of a stove having said new design.

The design for the top portion, A, consists of the overhanging lower plate, B, and inclined upper plate, C, both shaped, proportioned, ornamented, and arranged together so as to present substantially the same appearance as is represented in the aforesaid photograph.

20 The design for the overhanging angular plates B and D consists of the outer plain inclined parts, a, and upper convexly-curved portions, b, shaped, disposed, and ornamented substantially as represented in the aforesaid photograph.

25 The design for the panel E consists of the compound end ornaments, c, and top and bottom oblong ornaments, d, all shaped and arranged together upon the panel substantially as the aforesaid photograph represents the same.

30 The design for the panel F consists of the two compound end ornaments, e, and middle standing ornament, f, all shaped and arranged substantially as shown in the accompanying photograph.

35 The design for the front portion, G, consists of the two upper four-light doors, g, the two lower two-light doors, h, and the intermediate part, i, all shaped, proportioned, ornamented, and arranged together substantially as represented in the photograph aforesaid.

40 The design for the end section, H, consists of the upper four-light door, j, lower panel, I, and intervening band, k, all shaped, proportioned, ornamented, and arranged together substantially as shown in the aforesaid photograph.

45 The design for the panel I consists of the two end ornaments, l, united at top by scroll-

forms m and at the bottom by the ornamentation n, all composed, shaped, and arranged together substantially as represented in the photograph above mentioned.

50 The design for the foot-rails or fenders J K consists of the straight flat angular front bar, o, and the inwardly and upwardly curved end parts, p, all shaped, ornamented, and united substantially as shown in the photograph.

55 The design for the lower front part, L, consists of the compound end ornaments, q, and the middle compound ornament, r, each composed and all shaped and arranged together substantially as represented in the photograph aforesaid.

60 The design for the skirting M is composed of the ring-surrounded rosettes s, arches t, and angle-bars u along the lower edge, the upper obtuse-angled barred parts, v, and the intermediate compound ornaments, w, all shaped and arranged together so as to present substantially the same appearance as is represented in the aforesaid photograph.

65 The design for the legs N consists of the upper panels, x, having thereon the ornaments x', the upright angular foot y, and the intermediate concavely-curved and ornamented part, z, all shaped and arranged together as shown in the accompanying photograph.

70 What we claim as our joint invention is—

1. The design for the top A, composed of the parts B and C, shaped, proportioned, ornamented, and arranged together as described.

2. The design for the angular plates B and D, consisting of the parts a and b, shaped, ornamented, and arranged as described.

3. The design for the panel E, composed of the compound ornaments c and d, shaped and arranged together as set forth.

4. The design for the panel F, consisting of the compound ornaments e and f, shaped and disposed as described.

5. The design for the front portion, G, composed of the parts g h i, shaped, proportioned, ornamented, and arranged together as described.

6. The design for the end portion, H, consisting of the parts j I k, shaped, proportioned,

ornamented, and arranged substantially as described.

7. The design for the panel I, consisting of the ornamental parts $l m n$, as described.

5 8. The design for the fenders J K, composed of the parts o and p, shaped, ornamented, and combined as shown and described.

9. The design for the part L, composed of the compound ornaments q and r, shaped and arranged as specified.

10. The design for the skirting M, composed of the ornamental parts s t u v w, combined as described.

11. The design for the legs N, composed of the parts x, x', y, and z, shaped and arranged together as shown and described.

In testimony whereof we hereunto set our hands, in the presence of two subscribing witnesses, this 20th day of April, 1883.

H. CLAY BASCOM.
TOBIAS S. HEISTER.
